UNITED STATES PATENT OFFICE.

WILLIAM L. HOWE, JR., OF OVERLAND, MISSOURI.

DESIGN FOR A STEERING-POST BRACE.

Application filed January 15, 1923. Serial No. 4,888. Term of patent 7 years.

To all whom it may concern:

Be it known that I, WILLIAM L. HOWE, Jr., a citizen of the United States, residing at Overland, St. Louis County, Missouri, have invented a certain new, original, and ornamental Design for a Steering-Post Brace, of which the following is a specification, reference being had to the accompanying drawing, forming a part thereof, in which—

Figure 1 is an inverted plan view,
Figure 2 is a side elevational view, and
Figure 3 is a plan view of a steering post
brace embodying my new design.

I claim:

The ornamental design for a steering post
brace, substantially as shown.

WILLIAM L. HOWE, Jr.
